UNITED STATES PATENT OFFICE.

HARRIE A. BALLARD, OF SOMERVILLE, MASSACHUSETTS, ASSIGNOR TO THE BOYLSTON MANUFACTURING COMPANY, OF BOSTON, MASSACHUSETTS, A CORPORATION OF NEW JERSEY.

TREADLE MECHANISM FOR BED-LASTING MACHINES.

1,117,300.

Specification of Letters Patent. Patented Nov. 17, 1914.

Application filed January 11, 1907. Serial No. 351,813.

To all whom it may concern:

Be it known that I, HARRIE A. BALLARD, of Somerville, in the county of Middlesex and State of Massachusetts, have invented 5 certain new and useful Improvements in Treadle Mechanism for Bed-Lasting Machines, of which the following is a specification.

This invention has relation to machines 10 for lasting shoes, and more particularly to that class of such machines known as "bed-lasters," in which the edge of the upper of a shoe is pulled over the inner sole at the toe and heel of the partially formed shoe. 15 This embodiment of the invention is in principle similar to that contained in the application Ser. No. 198,420, filed by me March 15, 1904 but involves four distinctly novel features. In the machine illustrated upon 20 the accompanying drawings, the lasting operation is precisely the same as that for which the invention previously referred to was designed.

The object of the present invention is to 25 provide for a lasting machine of this type, certain improved instrumentalities designed to facilitate the operations by which the shoe is to be lasted.

The machine herein illustrated comprises 30 two sets of wipers independently operative and mounted on separate carriages which are adapted to be moved toward and from each other, and means for supporting a shoe between the two sets of wipers, said 35 supporting means comprising a yielding main jack and a yielding toe jack arranged side by side and adapted to support the shoe in operative position.

The carriages referred to are provided 40 with manually operative means for moving them with their respective wipers to and from operative position relatively to the shoe, and each is further provided with an actuator for actuating its respective set of 45 wipers so as to engage and operate upon the upper of the shoe.

The instrumentalities so far described do not in any wise differ from those employed in the machine of the aforesaid application,

but I provide in the present invention independent manually operative means for moving the carriages and wipers away from the shoe. The last named means is so constructed and arranged with relation to the two jacks that, in addition to moving the wipers as described, it automatically retracts the jacks in opposition to their respective yielding means so slightly as to relieve the pressure of the shoe against the wipers prior to and during retrograde movement of the wipers. By so relieving the pressure between the shoe and the wipers, the force required to move the wipers is lessened, and aside from that, the upper of the shoe is relieved of unnecessary chafing which would otherwise result when the wipers are withdrawn.

The first mentioned manually operative means by which the carriages with their wipers are moved into operative position, 70 are provided with locking means adapted to prevent retrograde movement thereof. The said locking means like those of the former machine consist of a ratchet and a manually controlled pawl for each. In the operation 75 of my former machine it was necessary to disengage each pawl from its ratchet by two separate operations in order to permit retrograde movement of the wipers. Now, in the present invention, I provide instrumentalities which are adapted to disengage the pawls simultaneously, and which are adapted to be actuated by the means hereinbefore referred to for imparting retrograde movement to the wipers. 80

The main jack and toe jack have their independently operative yielding means for normally holding them in operative position, and their independently operative treadles for retracting them from operative 90 position, the said treadles being arranged side by side. The means for actuating the hereinbefore mentioned means for imparting retrograde movement to the wipers, consists of a third treadle interposed between 95 the two jack treadles and resting upon a laterally extending yoke whose ends rest upon the jack treadles. When the third

treadle is depressed to actuate its several instrumentalities, it first effects the disengaging of the retaining pawls from their respective ratchets, then by reason of frictional resistance of the wiper carriages or whatever other resistance may be incumbent thereupon, the said treadle effects a slight retrograde movement of the jacks, thereby lessening friction of the shoe upon the wipers, and last a retrograde movement of the carriages.

As previously stated each carriage is provided with an actuator for its set of wipers, said actuator being adapted to be manually operated to open and close the wipers so as to engage and fold in the edge of the upper of the shoe. When the edge of the upper is folded inwardly by the wipers, any preferred method of fastening the inturned edge may be performed, the latter having no bearing upon the present invention. But unless some means is provided for automatically moving the actuators so as to open the wipers when the latter are moved bodily away from the work, it is necessary to restore each set of wipers independently to open position prior to a subsequent wiping operation. The object of the present invention is to so connect the wiper actuators as to cause them, when bodily moved in opposite directions, to automatically open the wipers.

In summing up the results attained by the novel devices incorporated into the machine, it will be seen that one is the retrograde bodily movement manually imparted to the two wiping mechanisms, second, the unlocking or releasing of the carriages supporting the wipers, third, the depressing or retrograde movement imparted to the jacks, and fourth, the movement automatically imparted to the wiper actuators causing them to restore the wipers to their open or initial position.

Referring to the accompanying drawings forming part of this specification,—Figure 1 is a front elevation of a bed-lasting machine provided with the instrumentalities designed in accordance with this invention. Fig. 2 is a perspective view of the coöperating treadle mechanisms. Fig. 3 is a sectional plan view of the treadle mechanisms taken on the line 3—3 of Fig. 1. Fig. 4 is a front elevation of the yoke connecting the treadles together with the treadles in vertical section. Fig. 5 is a cross section on a line passing through the fulcrum of the bell crank levers. Fig. 6 is a detailed view of one of the bell crank arms and a portion of its actuator. Fig. 7 is an end elevation of one of the wiper carriages. Fig. 8 is a plan view of the fore-part of a shoe and the toe-wiping mechanism in operative engagement therewith. Fig. 9 is a plan view of a shoe together with the heel and toe-wiping

mechanisms in their relatively operative and inoperative positions, shown by full and dotted lines.

The same reference characters indicate the same parts wherever they occur.

The frame 10 of the machine is provided with guides 11 for a vertically movable main jack 12, and with parallel guides 13 for the vertically movable toe jack 14. The jacks 12 and 14 are provided with collars 15 adapted to be engaged by helical springs 16 coiled about the jacks so as to normally force the jacks upwardly. The upward movement of each jack is limited by an adjustable fixed stop 17 which normally impinges against a portion of the frame 10. The upper end of the jack 12 is provided with an oscillatory post or stud 18 which is fulcrumed upon a laterally extending pin 19, and which is adapted to enter the hole which is customarily provided in a last for this purpose. By reason of the oscillatory movement of which the post 18 is capable, the toe portion of a last and shoe mounted thereon is adapted to bear upon the upper extremity of the toe jack 14. The arm 18 has a laterally extending arm 20 which is connected to a spring 21, and which by reason of the tension of said spring exerts a yielding pressure which normally forces the toe portion of the shoe downwardly upon the toe jack. The two jacks are provided with independently adjustable instrumentalities by which the shoe supported thereon may be adjusted to various positions, so as to meet whatever requirements exist, and since the adjustability of the shoe forms no part of this invention a detailed description of these instrumentalities is omitted. The frame 10 is also provided with guides 22 and 23 which extend transversely of the line of movement of the jacks but in alignment with each other.

24 and 25 indicate respectively the carriages which support the heel and toe-wiping mechanisms. The arrangement of the guides and their carriages is such that the heel carriage 24 is movable toward and from the heel portion of a shoe mounted on the jacks, and the toe carriage 25 is movable toward and from the toe portion of the shoe. Each carriage is provided with a gear rack 26 extending longitudinally thereof on its under side, (see Fig. 7). The means for moving each carriage consists of a pinion 27 mounted on a transverse shaft 28 and adapted to coöperate with the rack 26. A hand wheel 29 is affixed to each shaft 28 and adapted to be manually rotated to move the adjacent carriage in either direction. The hand wheels 29 are provided with ratchets 30 which are adapted to be engaged by pawls 31 fulcrumed upon stud shafts 32. The pawls 31 are provided with arms 33 which by means of gravity normally hold

the pawls in operative engagement with their ratchets, and by means of which the pawls may be manually disengaged from the ratchets. The arrangement of the pawls and ratchets relatively to the hand wheels is such as to permit movement of the two carriages toward each other and the shoe but to prevent retrograde movement of the carriages.

Inasmuch as the details of the wiping mechanisms are not important in this invention, a brief description of certain portions thereof will be sufficient.

34 is the base carried by the heel carriage 24 and on which the heel-wiping mechanism is mounted. 35 is the base carried by the toe carriage 25 and on which the toe-wiping mechanism is mounted. The heel-wiping mechanism comprises a pair of wiping members 36 which are connected to and adapted to be actuated by a manually operative actuator 37 fulcrumed upon the base 34. The toe-wiping mechanism which is practically the same as the heel-wiping mechanism, and which is shown more in detail in Fig. 8, 25 comprises a pair of coöperating wipers 38 and a manually operative actuator 39 fulcrumed at 40 to a portion of the base 35. The wipers are pivotally connected together by a stud 41 and connected to the actuator 30 by suitable connecting pieces 42 and 43 whereby movement is communicated by the actuator to the wipers. Although the wipers may be opened or closed irrespective of the location of the carriages relatively to the shoe, they are in practice preferably left open at all times excepting when the carriages and wipers as a unit are in operative position nearest the shoe, as illustrated by dotted lines in Fig. 9. When the wiping mechanisms are in the last named position, they are adapted to be actuated by their actuators, so as to close the wipers over the sole of the shoe, as illustrated by Fig. 8. When the wipers are so actuated to fold in the upper of the shoe, the position to which the shoe is adjusted by means of the adjusting instrumentalities of the jacks, hereinbefore mentioned in a general way, is preferably such as to cause them to effect a slight retrograde movement of the shoe and jacks in opposition to the springs 16. The main jack 12 is provided with a treadle 44 by which it is adapted to be depressed, and the toe jack 14 is likewise provided with a treadle 45 by which it is adapted to be independently depressed. The rear ends of the treadles 44 and 45 project through apertures 46 formed in a cross-brace 47 affixed to the frame 10, and are thereby fulcrumed upon the said brace.

Those parts of the machine hereinbefore described do not to any material degree vary from parts of which the machine in my hereinbefore mentioned application is composed, and although the wiping mechanisms

and their instrumentalities common both to the machines of the present invention and the aforesaid application are not minutely described, it will be understood that they are provided with the same adjusting instrumentalities as formerly.

The present invention is not embodied in the aforesaid elements but in those herein-after described which are adapted to control and actuate the former.

Carriage - returning mechanism.—The means herein employed for returning one or both of the wiper carriages 24 and 25 simultaneously to their respectively distant or inoperative positions, are adapted to be actuated by a manually operative treadle 50, hereinafter termed the third treadle. This treadle is supported at two points which are adapted by reason of certain features hereinafter described, to alternate in operating as a fulcrum upon which the treadle operates. The member which under normal conditions acts as the fulcrum of the treadle 50 is a yoke 51 extending laterally across and overlapping the treadles 44 and 45 at points near those points where the said treadles are connected to their respective jacks. It may be seen therefore, that in a measure the treadle 50 is supported by and between the jacks and their elevating springs 16. One end of the treadle 50 is pivotally connected to a reciprocatory member or bar 52 which is movable vertically in guides 53 and 54. The guide 54 is formed in the cross-brace 47 midway between the apertures 46, and the treadle 50 extends forwardly therefrom between the treadles 44 and 45. The yoke 51 rests upon the treadles 44 and 45 solely by gravity, and it is maintained in the desired position thereon by means of notches 48 extending laterally across the upper edges of said treadles. The lower edge of the yoke 51 occupies the notches 48 and is adapted to be adjusted laterally therein by means of set screws 49, of which one is mounted in each end of the yoke and adapted to abut against the side of the adjacent treadle.

It will be seen that by means of the construction and arrangement of the yoke it may be adjusted more toward one or the other of the treadles 44 and 45. The middle portion of the yoke 51 is offset so as to form a V-shaped depression 55 upon the upper edge of which the middle portion of the treadle 50 bears. This point of contact is below the center of gravity of the yoke 51, and therefore preserves a correct position of the latter and at the same time prevents lateral movement of the treadle 50 relatively thereto. The bottom edge of the treadle at this point is provided with a laterally extending notch 56 which receives the top edge of the yoke and prevents endwise movement of the treadle 50 relatively to the yoke.

The reciprocating member 52 is provided with a collar 57 affixed thereto and supporting a cross-bar 58 which extends equidistantly in either direction to the sides of the machine. One face of the bar 58 extends parallel and close to the rear face of the frame 10, by means of which, it is prevented from turning about the member 52. The extremities of the bar 58 underlie and are adapted to engage and move a pair of inwardly extending arms 59 which are formed integrally with squared stud shafts 60, (see Figs. 1 and 5). The stud shafts 60 have cylindrical portions 61 which have bearing in ears 62 formed on the frame 10, and in which they are adapted to oscillate. The squared portions of said stud shafts occupy squared holes formed in upwardly extending arms 63 63 which with their respective arms 59 59 constitute bell crank levers. The upper ends of the arms 63 63 are pivotally connected by links 64 64 to the heel carriage 24 and the toe carriage 25 respectively (see Figs. 1 and 7). By means of the levers and links connected to the carriages, the treadle 50 is enabled to impart retrograde movement to both carriages or to either one which is in operative position. The arms 63 63 are further provided with ears 65 65 which are pivotally connected to rods 66 66. The lower ends of the latter extend through bosses 67 67 formed on the frame 10, and are provided with adjustable fixed stops 68 68 which are adapted to impinge against the bosses 67 67 when retrograde movement is imparted to the carriages and so to limit the movement of the latter. Under ordinary conditions in which it is assumed that no undue resistance is offered by the carriages 24 and 25, the yoke 51 serves as the fulcrum of the treadle 50, but it is hereinafter explained in what manner the yoke ceases to be the fulcrum of the treadle 50 and becomes a load instead.

Carriage-releasing mechanism.—As hereinbefore stated one of the results effected by operating the third treadle is to unlock or release the hand actuated means by which the wiping mechanisms are moved into operative position. This releasing or unlocking operation consists in disengaging the retaining pawls 31 31 from the ratchets 30 30 prior to imparting retrograde movement to the carriages 24 and 25. The means for so disengaging the pawls consists of certain instrumentalities interposed between the pawls and the reciprocating member 52 and adapted to be actuated by the latter. These instrumentalities comprise a forwardly extending arm 69 rigidly attached to the upper end of the member 52 and a pair of oppositely disposed arms 70 70 affixed upon the stud shafts 32 32 to which the pawls 31 31 are likewise affixed, as previously described.

The arms 70 70 extend toward and overlap

each other at a point directly over the extremity of the arm 69 and are adapted to be simultaneously elevated by the arm 69 when the member 52 is actuated to impart retrograde movement to the carriages 24 and 25. It will, therefore, be seen that in this way pawls 31 31 are moved out of co-operative engagement with the ratchets 30 30 during the first part of the movement of the member 52. Although the pawls 31 31 are adapted to be simultaneously disengaged from their ratchets, it is plainly shown that they may be independently disengaged by means of the arms 33 33 if so desired.

Automatic jack-depressing means.—As hereinbefore stated there is considerable pressure existing between the wipers and the inturned edge of the upper when the wipers are closed together thereupon, and if this pressure were not reduced prior to retrograde movement of the wipers, the said movement would be attended by considerable unnecessary friction and resistance. I therefore arrange the carriage-retracting mechanism so as to relieve such pressure prior to retractive movement of the carriages. The treadles 44 and 45 being fulcrumed in the cross brace 47 and adapted to be independently depressed to lower the jacks 12 and 14, are the only means provided for supporting the yoke 51, and it is therefore apparent that both treadles 44 and 45 may be simultaneously depressed by means of the yoke 51 when sufficient load is imposed upon the latter.

Assuming that the heel and toe carriages are in their operative positions relatively to the shoe and locked there by means of the ratchets, and that the heel and toe wipers are engaging and maintaining downward pressure upon the pulled over portions of the upper, and assuming further that downward pressure is imposed upon the treadle 50, the yoke 51 serves initially as the fulcrum of the treadle, causing the member 52 to rise and disengage the locking pawls 31 from the ratchets 30. Further upward movement of the member 52 is momentarily arrested by the wiper carriages which are not yet free to be retracted, the pressure of the wipers upon the work holding the carriages stationary. Before the pressure upon the treadle can be increased sufficiently to overcome the holding action of the wipers and work the springs 16 yield to such pressure and the work is retracted from the wipers. This frees the wiper carriages and they, through the member 52, respond to the pressure upon the treadle and recede until their retracting mechanism is arrested by the stops 67, provided for that purpose.

It is practically impossible to so adjust the tension of the spring 16 that, when the heel and toe of the shoe are operatively engaged and depressed by their respective

wipers, pressure of the heel wipers upon the shoe shall be exactly equal to the pressure of the toe wipers. In order to compensate for any difference of pressure exerted by two sets of wipers, the yoke 51 may be so adjusted with relation to the levers 44 and 45 that downward movement of the treadle 50 may exert through the yoke 51 a greater pressure upon that jack which is the more strongly supported by its spring 16. As previously stated, the yoke and consequently its point of contact with the treadle 50 may be adjusted toward or from either of the treadles 44 and 45 by means of the set screws 49 49. The object of providing this means of adjustment is explained in the following description: Assuming that the toe jack is forced upwardly by its spring 16 against the toe wipers with greater pressure than that by which the heel jack is forced by its spring against the heel wipers, it is obvious that in order to depress both jacks simultaneously, great downward pressure must be exerted upon the toe jack. Therefore, in order to cause downward movement of the treadle 50 to exert upon the toe jack a greater downward pressure than that exerted upon the heel jack, the yoke 51 is adjusted so as to position its point of contact with the treadle 50 closer to the treadle which actuates the toe jack. In all cases the aggregate pressure exerted by the yoke 51 upon the toe and heel treadles, is equal to that exerted upon the yoke by the treadle 50, and it is apparent that the distribution of that pressure depends entirely upon the relative positions of the points of contact between the yoke and the three treadles. When the point of contact with the treadle 50 is midway between the points of contact with the treadles 44 and 45, pressure upon the latter treadles is equalized, but they may be made to exert more on one jack treadle and less on the other jack treadle by adjusting the point of contact with the treadle 50 nearer to that jack treadle which is to receive the greater proportion of the pressure.

Automatic wiper-opening mechanism.— As previously stated in the description of the wiper mechanisms, the heel wipers and toe wipers are adapted to be independently and manually operated by means of the actuators 37 and 39. Inclosing the two sets of wipers over the work, it is desirable to actuate first one set and then the other and to leave them in their closed or operative positions so long as they are in position to engage the work. Heretofore it has been necessary to restore the wipers to open position independently of whatever other movement may have been imparted thereto. The wiper-opening mechanism provided in this invention is adapted to utilize the retrograde bodily movement of the wipers

to effect simultaneous opening of the latter, by means of a member connecting the two wiper actuators. The said member is illustrated as having the form of a chain 70 (see Figs. 1 and 9). The ends of the chain 70 are connected to the rear ends 71 72 of the actuators 37 39 respectively. The ends 71 72 of the actuators are on the opposite sides of the fulcra 40 40 with relation to the connecting members 42 by which the actuators 75 impart movement to the wipers.

Assuming that the means connecting the ends 71 72 is of the correct length, the actuators are free to be moved to close the wipers, as shown by dotted lines in Fig. 9. The length of the member 70 is preferably a little greater than the distance between the points of connection with the ends 71 72 when the latter are in the position just described. When the wiping mechanisms are moved bodily away from the work, the member 70 holds the rearward extremities of the actuators thereby preventing little or no separation of said extremities, and as the fulcra 40 40 continue to move with their respective mechanisms, they actuate the actuators so as to restore the wipers to their open position. The latter position of the actuators is illustrated in Fig. 1 and by full lines in Fig. 9. Restoring movement would likewise be imparted to only one of said actuators if the latter's wiping mechanism were the only one to be moved away from the work, although of course in that case, the movement imparted to the actuator would be approximately one-half as great as that when both wiping mechanisms are moved to their relatively distant positions.

A detail of construction by which suitable adjustment is provided for the carriage-returning mechanism is illustrated by Figs. 5 and 6. The range of movement of the member 52 is invariable, and in order to insure the great amount of retrograde movement to be imparted to the wiper carriages, some means by which this movement may be adjusted irrespective of the movement of said member is desirable. The said adjusting means is shown on the drawings and comprises a series of apertures 73 formed in the arms 59 59 at various distances from the shaft 60 from which said arms extend. Each of the arms 59 is provided with a screw-threaded bolt 74 which is adapted to occupy any one of the holes 73, 115 and to be provided with one or more washers 75 and a screw threaded nut 76. The bolt 74 may be provided with the desired number of washers 75, and then passed upwardly through the desired hole 73 so that 120 its screw-threaded end projects above the arm 59 and is screwed in place by the nut 76 which is adapted to draw up the head of the bolt against the washers and to clamp them firmly against the under side of the 130

arm. The head of the bolt 74 is adapted when so attached to be engaged by the cross-bar 58 when the latter is raised and to transmit movement to the arm. Any desirable number of washers 75 may be supplied to cause the head of the bolt to project below the arm 49 far enough to eliminate undue clearance between the cross-bar and the arm. Further than taking up lost motion of the cross-bar, bolt 74 may be utilized to impart oscillation of more or less degrees to the arm 59 by inserting the bolt in the hole 73 farther from or nearer to the shaft 60. By providing means for engaging the cross-bar which may be shifted toward or from the center about which the arm 59 oscillates, the operative radius of the arm may be varied so as to effect a variable range of movement in the levers which retract the wiper carriages.

Having thus explained the nature of the invention and described a way of constructing and using the same, although without attempting to set forth all of the forms in which it may be made, or all of the modes of its use, I declare that what I claim is:—

1. A lasting machine comprising a plurality of work-supports capable of independent jacking movement, a plurality of carriages for the wipers, a treadle, and means connecting the treadle with the supports and carriages whereby said supports and carriages may all be actuated by a movement of the treadle.

2. A lasting machine comprising a plurality of work-supports capable of independent jacking movement, a plurality of carriages for the wipers, a treadle, means actuated by the treadle for moving said supports in unison, said means being also adapted to effect movement of said supports independently of each other, and means connecting the treadle with the carriages for moving the carriages.

3. A machine for operating upon boots and shoes, comprising a movable work support, an instrumentality for operating upon the work, a treadle, means arranged to transmit motion from said treadle for retracting the work from said instrumentality, and means arranged to transmit motion from said treadle for retracting said instrumentality from the work.

4. A lasting machine comprising a plurality of supports for the work, a plurality of carriages for the wipers, locking means for the carriages, a treadle, and means operable by a movement of the treadle for releasing said locking means, moving the work supports, and moving the carriages.

5. A lasting machine comprising heel-wiping mechanism, toe-wiping mechanism, a pair of carriages, one for the heel-wiping mechanism, and the other for the toe-wiping mechanism, said carriages being movable in

alignment toward and from each other, a jack for supporting a shoe between said carriages, means adapted to be actuated by hand to move the heel carriage to operative position, interlocking means engaging said hand-actuated means and adapted to normally prevent retrograde movement of the carriage, means adapted to be actuated by hand to move the toe carriage to operative position, interlocking means engaging said second hand-actuated means and normally adapted to prevent retrograde movement of the toe carriage, and treadle mechanism adapted to move said locking means out of locking position and to impart retrograde movement to both of said carriages.

6. A lasting machine comprising a yielding jack for the work, wiping means movable toward and from the work, means for retracting the wiping means from the work, and a treadle so connected to said jack and said retracting means as to retract the former or actuate the latter or both in the order of their lesser resistance.

7. A lasting machine comprising a plurality of yielding jacks for the work, a plurality of carriages for work-engaging instrumentalities movable toward and from the work, means for retracting such carriage or carriages as are relatively near the work, a treadle so connected to the jacks and to said retracting means as to retract the former or actuate the latter or both in the order of their lesser resistance, and instrumentalities mounted on said carriages for operating upon and frictionally engaging the work with such friction as to render the resistance of said retracting means greater than that of the jacks.

8. A lasting machine comprising a pair of movable jacks for the work, a plurality of carriages movable toward and from the work, instrumentalities mounted on said carriages for operatively engaging the work, means for forcing the jacks with yielding force toward their operative positions, a pair of treadles, one for each jack, adapted to retract the jacks from operative position, a yoke connecting and supported by said treadles, a third treadle fulcrumed upon the yoke between the jack treadles, and means connected to and adapted to be actuated by said third treadle to impart movement to said carriages, said means being adapted to be the fulcrum of said third treadle at the point of connection therewith, thereby rendering the third treadle adapted to actuate the jack treadles.

9. A lasting machine comprising a pair of jacks movable in parallel directions, independently yielding means for each of the jacks, for forcing them in one and the same direction, a pair of independent treadles for retracting the jacks independently and in opposition to their yielding means, a yoke

- of which each end is supported by one of the treadles, a third treadle fulcrumed upon the yoke between said retracting treadles, a reciprocatory member engaging and 5 adapted to be actuated by said third treadle and when held stationary to become the fulcrum of said treadle and thereby effect a retracting movement of either or both of the retracting treadles when the third 10 treadle is actuated, and means for adjusting said yoke and its fulcrum point toward or from either of the retracting treadles so as to impose more or less of its load upon either of the same.
- 15 10. A lasting machine comprising a pair of jacks movable in parallel directions, means for yieldingly forcing the jacks in one and the same direction, a pair of independent treadles for retracting the jacks independently and in opposition to their yielding means, a yoke of which each end is supported by one of the treadles, a third treadle fulcrumed upon the yoke between said retracting treadles, a reciprocatory member 20 connected to and adapted to be actuated by said third treadle, and means adapted to be actuated by said reciprocatory member and to offer resistance of varying degrees which, when transmitted back to said third treadle 25 is in excess of the resistance of said yoke, renders the point of connection between the third treadle and reciprocatory member the fulcrum of said third treadle, whereby actuation of said third treadle produces 30 bodily movement of said yoke.
11. A lasting machine comprising a treadle having two points of support either adapted to serve as a fulcrum while the other is moved, a movable work support 40 connected with the treadle at one of said points and adapted to be moved thereby, movable means for operating upon the work, and means connected with said treadle at the other of said points and with said 45 movable means and adapted to be actuated by the treadle and to serve as the fulcrum thereof to effect actuation of the work support.
12. A lasting machine comprising a plurality of sets of wipers, an actuator for each set of wipers adapted to open and close the same, a carriage for each set of wipers and actuator, and means connecting said actuators and adapted to actuate them when the latter are moved bodily in predetermined 55 directions.
13. A lasting machine comprising a jack for the work, two sets of wipers, an actuator for each set of wipers adapted to open 60 and close the same, a carriage for each set of wipers and actuator, said carriages being movable toward and from the work, and means connecting said actuators and adapted to actuate them to open the wipers when 65 they are moved bodily away from the work.
14. A lasting machine comprising a plurality of work-supports capable of independent jacking movement, a plurality of carriages, a treadle, means actuated by the treadle for moving said supports, and means 70 actuated by said treadle for moving said carriages away from operative position.
15. A machine for operating upon boots and shoes, comprising a movable work support, an instrumentality movable toward and from the work for operating upon the work, a carriage for said instrumentality, means for locking said carriage in operative position, a treadle, and means operative by said treadle for unlocking said carriage and 75 moving said carriage and work support.
16. A machine for operating upon boots and shoes, comprising a movable work support, an instrumentality for operating upon the work, a treadle, means arranged to transmit downward movement of said treadle for retracting the work from said instrumentality, and means arranged to transmit further downward movement of said treadle for retracting said instrumentality from the work.
17. A machine for operating upon boots and shoes, comprising a movable work support, a plurality of carriages movable independently of each other, instrumentalities mounted on said carriages for operating upon the work, means for locking said carriages, a treadle, and means operative by said treadle for unlocking said carriages and moving said carriages and work support.
18. A machine for operating upon boots and shoes, comprising a movable work support, a plurality of carriages movable independently of each other, instrumentalities mounted on said carriages for operating upon the work, means for locking said carriages, a treadle, and means operative by said treadle for unlocking said carriages and moving said work support.
19. A machine for operating upon boots and shoes, comprising a jack for the heel end of a piece of work, a jack for the toe end of such piece of work, said jacks having individual jacking springs and being capable of jacking and unjacking movement independently of each other, devices arranged to operate respectively upon the heel end and toe end of such piece of work, a treadle, means operable by said treadle for imparting unjacking movement to both of said jacks, and means operable by unjacking movement of said treadle for retracting said devices from such piece of work.
20. A machine for operating upon boots and shoes, comprising a jack for the heel end of a piece of work, a jack for the toe end of such piece of work, said jacks being capable of jacking and unjacking movement independently of each other, means for operating upon the heel end of such piece of

- work, a carriage for said means, means for operating upon the toe end of such piece of work, a carriage for the last-mentioned means, a treadle, means arranged to transmit movement from said treadle for imparting unjacking movement to both of said jacks, and means arranged to transmit such movement of said treadle for imparting retractive movement to both of said carriages. 5
- 10 21. A machine for operating upon boots and shoes, comprising a plurality of independently movable work supports, a plurality of independently movable carriages, means for locking said carriages, devices mounted upon said carriages for operating upon the work, a treadle, and means operative by said treadle for unlocking said carriages and for moving said carriages and said work supports. 15
- 15 22. A machine for operating upon boots and shoes, comprising a plurality of independently movable work supports, a plurality of independently movable carriages, means for locking said carriages independently of each other, devices mounted upon said carriages for operating upon the work, a treadle, and means operative by said treadle for unlocking said carriages and for moving said carriages and said work supports. 20
- 20 23. A machine for operating upon boots and shoes, comprising a movable work support, a plurality of carriages, devices mounted upon said carriages for operating upon the work, said carriages being movable in different directions from the work, a treadle, and means operative by said treadle for moving said carriages away from the work and for moving said work support. 25
- 25 24. A lasting machine comprising a heel jack, a toe jack, end wiping mechanisms for lasting a shoe supported on said jacks, each of said mechanisms including a sliding carriage, wipers thereon and an actuator for the wipers, a treadle for each of said jacks for effecting a relative vertical movement of each jack and the corresponding end wiping mechanism, and mechanism including a treadle supplemental to the first-mentioned 30 treadles for effecting a simultaneous relative vertical movement of both jacks and their corresponding end wiping mechanisms. 35
- 30 25. A lasting machine comprising wiper mechanism, a sliding carriage therefor, means for locking said carriage to hold the same in working position, and treadle mechanism arranged to move said locking means to release said carriage and to retract said carriage from working position. 40
- 40 26. A lasting machine comprising wiper mechanisms, sliding carriages for said mechanisms, said carriages being movable independently, independently locking means for each of said carriages, and treadle mechanism arranged to actuate said locking means to release said carriages, and to retract said carriages. 45
- 50 27. A lasting machine comprising wiper mechanism, a sliding carriage therefor, a ratchet and coacting pawl arranged to lock said carriage against movement away from working position, and treadle mechanism arranged to disengage said ratchet and pawl and retract said carriage. 55
- 55 28. A lasting machine comprising wiper mechanisms, independently movable carriages therefor, ratchets and pawls arranged to lock said carriages independently of each other against movement away from working position, and treadle mechanism arranged to disengage said pawls from said ratchets and to move said carriages from working position. 60
- 60 29. A lasting machine comprising wiper mechanism, a carriage therefor, means adapted to lock said carriage against movement away from working position, a treadle, and mechanism operable by a simple movement of said treadle in one direction and arranged to actuate said locking means to release said carriage and to move said carriage away from working position. 65
- 65 30. A lasting machine comprising a carriage, a wiper movably mounted thereon, and means arranged to actuate said wiper relatively to said carriage in consequence of movement of said carriage. 70
- 70 31. A lasting machine comprising a carriage, a wiper movably mounted thereon, and means arranged to move said wiper away from the working position relatively to said carriage in consequence of movement of said carriage away from working position. 75
- 75 32. A lasting machine comprising shoe-supporting means, a wiper, movable means for carrying said wiper to and from working position in a plane substantially parallel to the plane of the sole of the shoe, one of said means being otherwise movable to relieve the pressure of said wiper upon the pulled-over portion of the shoe upper, a treadle, mechanism operable by a movement of said treadle to impart pressure-relieving movement to said one of said means as aforesaid, and means operable by such movement of said treadle to retract said wiper-carrying means in said plane. 80
- 80 33. In testimony whereof I have affixed my signature, in presence of two witnesses. 85
- 85 HARRIE A. BALLARD.
- Witnesses:
CHARLES S. JOHNSON,
A. L. FOLSOM.
